Primary Examiner — Khawaja Anwar*Assistant Examiner* — Julice Seung Eun Oum(74) *Attorney, Agent, or Firm* — Justin Lampel(57) **CLAIM**

The ornamental design for an exercise sword as shown and described.

DESCRIPTION

FIG. 1 is a perspective view of an exercise sword showing my new design;

FIG. 2 is front view thereof;

FIG. 3 is a side view thereof;

FIG. 4 is a top view thereof; and,

FIG. 5 is a bottom view of the exercise sword.

The broken lines are for illustrative purposes only and form no part of the claimed design.
